(57) **CLAIM**

The ornamental design for a device for measuring vital signs assembly, as shown and described.

DESCRIPTION

FIG. 1 is a perspective view of a device for measuring vital signs assembly showing our new design with the main body inserted into a band;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is an exploded view showing the state in which the main body is being inserted into the band; and,

FIG. 8 is a perspective view showing the state in which the main body is hanging on a necklace.

The broken lines depicting the necklace seen in FIG. 8 are for purposes of illustrating an environment of use and form no part of the claimed design. The dot-dash lines in the FIG. 7 exploded view indicate the order of assembly, and also form no part of the claimed design.
